UNITED STATES PATENT OFFICE

JAMES B. HASKELL, OF LONGVILLE, MINNESOTA

DOOR OPERATOR

Application filed January 5, 1931. Serial No. 506,576.

My invention provides an extremely simple, low cost but highly efficient door operator especially adapted for opening and closing garage doors, but adapted generally for the opening and closing of swinging closures; and generally stated, the invention consists of the novel devices, combinations of devices, and arrangement of parts hereinafter described and defined in the claims.

This improved door operator includes as its major element a lever of novel construction connected and operated in a novel manner. The power device for operating this lever may take various forms which should be an extensible connection such as a cylinder and piston, a rack and pinion or the like arranged to transmit power from a fixed base of reaction to an offset portion of the lever and through the lever directly to the door. A reciprocating motor made up of cylinder and piston is especially adapted to be operated by compressed air and hence such a device is designated as a pneumatic door operator; but it will be understood that the term "pneumatic" as well as the term "door" is used in a liberal sense, the former to include fluids under pressure, and the latter to indicate swinging closures such as are more commonly designated as doors and gates.

In the accompanying drawings, which illustrate the invention, like characters indicate like parts throughout the several views.

Referring to the drawings:

Fig. 1 is a fragmentary view in front or outside elevation showing the door operator applied to a garage door;

Fig. 2 is a horizontal section taken on the line 2—2 of Fig. 1; and

Fig. 3 is a view partly in elevation and partly in vertical section showing the cylinder, piston and co-operating air control connections including a reversible two-way valve.

In Figs. 1 and 2, the door framework is indicated by the numeral 4 and the door which is connected to the framework by hinges 5, is indicated by the numeral 6. Rigidly secured on the door at the outer side thereof is a bracket 7 provided with an upwardly pro-

jecting roller-equipped stud 8. The numeral 9 indicates a bracket that is rigidly secured to the framework 4 above the top of the door at a point above the door opening, inward from the door hinge 5 but outward of the bracket 7. The bracket 9 is provided with a depending stud 10 to which is pivoted one end of a cam-acting lever 11. This lever 11 is provided with a long cam slot or cam-way 12 in which the roller-equipped stud 8 of the door bracket 7 is arranged to work. Outward of its slot 12, the lever 11 is provided with an intermediate laterally offset crank-acting portion 13 to which a head 14 is pivoted.

The cylinder 15 of the reciprocating motor, at one end, is pivotally connected at 16 to a bracket 17 rigidly secured on the framework 4 above the intermediate portion of the door opening. Working in the cylinder 15 is a piston 18, the stem 19 of which works through a stuffing box 20 in the free end of the pivoted cylinder. The projecting end of the piston stem 19 is secured to the pivoted head 14 and hence is pivotally connected to the offset portion 13 of the cam-acting lever 11.

Small flexible air pipes 21 and 22 are connected, respectively, to the pivoted and free end portions of the cylinder 15. These pipes 21 and 22 extend from ports 23 and 24, respectively, to a valve casing 25 that is suitably supported on the upper portion of the door framework 4. This valve casing 25 has an air inlet port 26 and an air exhaust port 27. An air pipe 28 that extends from a suitable source of air under compression is connected to the air intake port 26. Working in the valve casing 25 is an oscillatory valve head 29 that is connected to an operating arm 30 exposed outside of the casing 25. This valve head can be operated either manually at will, or automatically, but for the purpose of this case may be a hand-operated valve.

The positions of the various parts when the door is closed are indicated by full lines in Figs. 1 and 2, and the positions of the parts when the door is opened are indicated by dotted lines in Fig. 2. Also Fig. 3 indicates the position of the valve head 29 and of the

piston when the door is closed. When the valve head 29 is in the position shown by full lines in Fig. 3, compressed air will be delivered into the outer end of the cylinder 5 and the inner end of the cylinder will be connected to exhaust, and, of course, that is the position in which said valve head will be set to cause closing of the door. When the door is to be opened, the valve head and its arm are 10 oscillated to the position shown by dotted lines in Fig. 3, thereby connecting the inner end of cylinder 15 to compressed air supply and the outer end of said cylinder to exhaust, and this, of course, will cause the piston to 15 move outward or toward the free end of the cylinder.

The crank-acting portion of lever 11 will, of course, have its greatest effective length when moved at approximately a right angle to the 20 plane of the door opening. In the initial door-opening movement, the said crank-acting portion 13 of lever 11 has considerably less than its maximum effective length or leverage, but at that time, the roller-equipped 25 stud 8 of the door bracket 7 is located in the cam slot 12 very close to the lever pivot 10 so that the door will be given a very slow initial opening movement but under very effective and relatively great force from the cylinder 30 and piston. When the door is in its closed position, shown by full lines in Fig. 2, stud 8 is at the inner extremity of slot 12 of lever 11 and crank 14 is relatively close to its dead center in respect to pivots 10 and 16. With this 35 arrangement, under opening movement of the door as the stud 8 moves outward of slot 12, the direct effect is to start the opening movement of the door with relatively great power and slow movement, and as the stud 8 moves 40 outward in slot 12, the direct effect is to increase the speed of movement of the doors since the ratio of the distances of stud 8 and pin 14 from pivot 10 increases, and a small arcuate movement of pin 14 causes a relatively 45 large arcuate movement of stud 8. Indirectly, the outward movement of stud 8 in slot 12 decreases the speed of movement of pin 14 by increasing the lever arm of the resisting force (of the door), and this offsets 50 to some extent the direct effect of the outward movement of stud 8. The direct effect is further offset by the decreasing speed of rotation of the crank 13, as the same approaches its dead center. The net or resulting effect 55 with the arrangement illustrated and described is to start both opening and closing movements with relatively great power and slow speed, and to increases the speed of the door opening and closing movements between 60 extreme positions.

This arrangement affords the desired slow movements and relatively great power for starting the door both from closed and open positions, and gives an accelerated or relatively rapid intermediate movement to the door. 65

Again referring to Fig. 2, it will be noted that when the door is closed, the lever 13 lies close to the door frame with its slot 12 parallel thereto. By mounting the cylinder to oscillate, intermediate connections such as 70 links between the piston and the lever are made unnecessary.

The operator, as shown, is supplied to but one door. Where double swinging doors are used, two operating devices may be employed, 75 one for each door, in which case both operators could be operated simultaneously by a single valve. Also if preferred, a single operator could be used for two doors and the one door connected to the other for simultaneous 80 swinging movements by devices such as hitherto provided and well known for that purpose.

Very obviously, a device such as this can be 85 quickly applied to garage doors and the like. It is important, however, that the brackets 7 and 9 be applied in quite close normal relation and that they should both be applied a considerable distance inward from the door hinge so that the force from the motor 90 will be more effective in moving the door and would produce less strain on the door than with the said brackets applied close to the axis of the door hinge. 95

What I claim is:

1. The combination with a door frame and a door hinged thereto, of a bracket applied to the door inward of its hinge, a second bracket applied to the door frame above the door between the door hinge and the door bracket, a cam acting lever pivoted to the second noted bracket and having a long cam slot and an intermediate laterally-projecting crank portion, said door bracket having a projection working in the slot of said cam lever, a cylinder support secured to the door frame, a cylinder pivotally connected to said cylinder support at one end, and a piston working in said cylinder and having a stem connected to the crank-acting portion of said cam lever, and means for controlling a supply of motive fluid to said cylinder for reciprocating the same in one direction to open the door and in the other direction to close the door. 110

2. The combination with a door frame and a door hinged thereto, of a bracket applied to the door inward of its hinge, a second bracket applied to the door frame above the door between the door hinge and the door bracket, a cam acting lever pivoted to the second noted bracket and having a long cam slot and an intermediate laterally-projecting crank portion, said door bracket having a projection working in the slot of said cam lever, a cylinder support secured to the door frame, a cylinder pivotally connected to said cylinder support at one end, and a piston working in said cylinder and having a stem connected to the crank-acting portion of said 125 120 115 125 130

cam lever, and a reversible two-way valve mechanism connected to a source of compressed air supply and having conduits leading to the opposite ends of said cylinder.

3. The combination with a door frame and a door hinged thereto, of a bracket applied to the door inward of its hinge, a second bracket applied to the door frame above the door, a cam lever pivoted to the second noted bracket and having a long cam slot and an intermediate laterally projecting crank portion, said door bracket having a projection working in the slot of said lever, a cylinder mounted from the door frame, and a piston working in said cylinder and connected to the offset crank portion of said lever, and fluid pressure means for reciprocating said piston to open and close the door.

4. The combination with a door frame and a door hinged thereto, of a bracket applied to the door inward of its hinge, a second bracket applied to the door frame above the door, a cam lever pivoted to the second noted bracket and having a long slot and an intermediate laterally projecting crank portion, said door bracket having a projection working in the slot of said lever, and an endwise thrust connection anchored to the door frame structure and pivotally connected to the laterally projecting crank portion of said lever and operative on the latter to open and close the door.

5. The combination with a door frame having a door hinged thereto, of a bracket applied to the door inward of its hinge, of a second bracket applied to the door frame above the door, a cam lever pivoted to the second noted bracket and having a slot and an intermediate lateral projecting crank portion, said door bracket having a projection working in the slot of said lever, and an operating connection anchored to the door frame structure and attached to the laterally projecting crank portion of said lever and operative on the latter to open and close the door.

In testimony whereof I affix my signature.
JAMES B. HASKELL.
